[57] CLAIM

The ornamental design of a support frame for a roller skate, as shown and described.

DESCRIPTION

FIG. 1 is a left side elevational view of a support frame for a roller skate showing my new design;

FIG. 2 is a right side elevational view thereof;

FIG. 3 is a front elevational view thereof;

FIG. 4 is a rear elevational view thereof; and,

FIG. 5 is a top plan view thereof.

The supporting elements and wheels for the roller skate are shown in dotted lines only for illustrative purposes and form no part of the claimed design.
